UNITED STATES PATENT OFFICE.

WILLIAM T. JONES, OF DETROIT, MICHIGAN, ASSIGNOR TO EDMUNDS & JONES MFG. CO., OF DETROIT, MICHIGAN, A CORPORATION OF MICHIGAN.

OIL-BURNER FASTENER AND SPLASH-PREVENTER.

1,073,689.

Specification of Letters Patent. Patented Sept. 23, 1913.

Application filed December 27, 1909. Serial No. 534,949.

To all whom it may concern:

Be it known that I, WILLIAM T. JONES, a citizen of the United States, residing at Detroit, in the county of Wayne, State of Michigan, have invented certain new and useful Improvements in Oil-Burner Fasteners and Splash-Preventers; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an oil burner fastener and splash preventer, and consists in the construction and arrangement of parts hereinafter more fully set forth and pointed out in the claims.

The primary object of the invention is to provide fastening means for attaching a burner to a lamp font, wherein the arrangement is such as to prevent the oil splashing from the burner around or through the fastening means, and the use of solder in connecting the fastening parts with the lamp font is obviated.

A further object is to provide means for fastening a burner to a lamp font of such a character as to obviate the twisting of the wick, leaving the wick free to run into the wick tube and affording a free passage for the oil through the wick.

A further object is to provide for quickly and firmly attaching the burner to the font and readily detaching it therefrom.

A further object is to provide for strengthening the top of the font so as to firmly support the burner and resist the force necessary to exert in attaching the burner in place and in removing it from the font for the purpose of re-filling.

A further object is to provide a vent opening through which air may escape from the upper portion of the font around the depending splash-resisting tube through which the wick passes.

The above objects are attained by the structure illustrated in the accompanying drawings, in which:—

Figure 1 is a fragmentary view, partly in section, through the top portion of the font of an oil lamp. The burner which appears in elevation is shown attached to the font

by my improved fastening means. Fig. 2 is an inverted plan of the burner. Fig. 3 is an elevation of the tube which depends within the font and the base of the burner which is seated therein, the upper portion 60 of the burner being broken away. Fig. 4 is a similar view with the tube and its supporting disk in section, as on line 4—4 of Fig. 3. Fig. 5 is a fragmentary view in section through the base of the burner parallel with the wick tube. Fig. 6 is a similar view with the section line at right angles to that shown in Fig. 5.

Referring to the characters of reference, 1 designates the oil font, of which the upper 70 portion 1 is shown, and which may be of any desired shape. The body of the font is preferably formed of brass because of its ductility, and the top 2 thereof is spun onto the circular plate or disk 3 of steel, which 75 extends diametrically across the upper portion of the font and is confined in place by the top 2 which lies thereon, and the inwardly extending bead 4 which supports said disk. The steel disk 3 serves as a reinforcement which greatly strengthens the top 80 of the font. Formed integral with said disk and depending centrally therefrom is a tube 5 which extends downwardly to a point adjacent the bottom. The body portion of 85 said tube is straight, but the upper end thereof is made flaring, as shown at 6. In practice, the tube 5 is drawn out of the plate 3 and is shaped by suitable dies, thus forming the disk and tube without a seam or 90 joint.

Formed in the wall of the tapered portion 6 of the tube on opposite sides are the vertical slots 7, each of which is provided at its lower end with a short lateral slot 8, said 95 lateral slots extending in opposite directions.

The burner 9 may be of any suitable construction and is provided with the usual wick shaft 10. The base 11 of the burner is made tapering to coincide with the flaring 100 upper end 6 of the tube 5 into which it is adapted to closely fit. In the lower end of the base 11 of the burner is a circular plate 12 through which the wick tube 13 passes, said plate having the laterally projecting 105 lugs 14 on opposite sides thereof which lie in slots formed in the end of the tapered base 4, said plate being confined in the end of the tapered base by turning the marginal portion 15 of said base over onto said plate, 110

as clearly shown in Figs. 2 and 6. When the base of the burner is introduced into the flaring opening 6 of the tube 5, the lugs 14 are caused to register with and enter the slots 7 in the wall of said tube. When the base of the burner shall have been fully seated in the flaring opening of the tube, said lugs will lie in the plane of the lateral slots 8 so that by a slight rotation of the 10 base within the tube to the right, said lugs will be caused to engage under the inclined margins 16 (see Fig. 3) of the lateral slots 8, and lock the base of the burner securely within the flaring opening of the tube, so as 15 to effect a tight closure between said parts and detachably join them by a fastening of the bayonet joint type. To remove the burner it is only necessary to turn it slightly toward the left, so as to disengage the lugs 20 14 from the slots 8, when the burner may be lifted out of the tube. This arrangement facilitates the operation of fastening the burner to the lamp font and unfastening it therefrom, obviating the use of the threaded 25 connection between said parts commonly employed, the objection to which is that the oil will follow the thread between the connected parts and work out of the font, the splashing of the oil in the font as ordinarily 30 made conducing to this undesirable result.

By means of the structure shown herein, the splashing of the oil in the font of the lamp is largely overcome by the tube 5 depending therein. The small amount of oil 35 which stands within the tube 5 through which the wick passes, cannot be caused to splash by any movement to which the lamp may be subjected, while the oil which surrounds said tube can find no avenue of escape through the top, which as will be seen, 40 is without a seam or joint that will admit of the passage of the oil. The only openings through the wall of the tube are the slots 7 and 8, and these are closed by the tapered base of the burner when it is seated therein, 45 while said base is fitted so tightly in the tapered opening of the tube 5 as to preclude the possibility of the oil passing between the tapered base and the wall of said tube.

50 By doing away with a threaded connection between the burner font, the necessity for rotating the burner many times in making a connection between the font and burner is obviated, thereby overcoming any 55 twisting of the wick to wring the oil there-

from, or interfere with the free passage thereof through the wick tube. A further advantage in this arrangement resides in the fact that the oil cannot splash onto the wick and thereby cause a flickering or variation of the flame. 60

As the lower end of the tube 5 extends nearly to the bottom of the lamp font, it is necessary to provide a vent for the font around said tube. This vent is afforded by 65 the slots 7 through which air may escape as the font of the lamp is being filled.

Having thus fully set forth my invention, what I claim as new and desire to secure by Letters Patent, is:—

1. A burner fastener and oil splash preventer comprising a disk secured in the top of an oil font having a tube extending centrally therefrom into said font, the upper portion of said tube being tapering to form a receiving socket for the burner base, a burner having a tapered base to enter and fill said socket in a manner to effect a tight closure between said parts, and interlocking members upon said base and socket for detachably connecting said parts together. 75

2. A burner fastener and splash preventer comprising a disk secured in the top of the burner font and having a tube depending centrally therefrom, the metal of the font at 85 the top lying upon the upper surface of said disk and a rib in the wall of the font supporting said disk below, a tube depending from said disk having slots in the wall thereof near its upper end, a burner having a base portion adapted to enter said tube, said base portion having projecting parts which engage in said slots to lock the base of the burner within said tube. 90

3. A burner fastener, comprising a socket tube depending within the font and supported by the top thereof, the wall of said tube having an angular slot therein, a burner having a base adapted to enter said tube to seat therein, said base having at its lower end a plate provided with a projecting lug adapted to engage in said angular slot to lock the base of the burner within said tube. 95

In testimony whereof, I sign this specification in the presence of two witnesses.

WILLIAM T. JONES.
